UNITED STATES PATENT OFFICE.

GIDEON F. SHERWOOD, OF SALEM, OREGON.

SLIDING GATE.

SPECIFICATION forming part of Letters Patent No. 440,283, dated November 11, 1890.

Application filed March 24, 1890. Serial No. 345,030. (No model.)

To all whom it may concern:

Be it known that I, GIDEON F. SHÉRWOOD, a citizen of the United States of America, residing at Salem, in the county of Marion and State of Oregon, have invented certain new and useful Improvements in Sliding Gates, of which the following is a specification, reference being had therein to the accompanying drawings.

10. This invention has relation to sliding gates, but more especially to that class known as "pulley-openers;" and my object is to produce a more simple, cheap, durable, and easily-operated device of such class than has hitherto been in use.

With this end in view my invention consists in the peculiar features of construction and combinations of parts more fully described hereinafter, and pointed out in the claims.

20. Referring to the accompanying drawings, Figure 1 is a perspective view of my complete device, the gate being shown in closed adjustment; and Fig. 2, a similar view showing the gate open to its farthest extent.

25. The reference-letter A indicates the gate, which may be of any preferred construction, but in the present instance consists of a pair of horizontal rails U and iron pickets introduced through them, and is suspended from

30. and supported by a suitable frame, consisting of the upright posts B, preferably three in number, and the top beam C, which rests at its middle and ends on said posts. This beam C is provided with a metallic track or way E extending its entire length, and the gate is

35. suspended by means of its end stiles D, which extend to the beam C and have secured to their upper ends anti-friction hangers F, traveling on the way E, and consisting of suitable

40. brackets in which are loosely mounted rollers f, having play the length of said brackets.

The mechanism for reciprocating the gate is as follows: Through suitable bearings secured to the center post B and situate about

45. half-way between the top of the gate and the upper end of said post, extends transversely a shaft H, preferably made of hollow piping, and on this shaft near the post is rigidly mounted a grooved wheel or pulley G. The

50. shaft H extends a considerable distance on each side of the post B, and its outer ends are supported by and have bearings in brackets

K, secured on the upper ends of posts J, and beyond said brackets the shaft ends have handles or crank-arms I, by means of which 55 said shaft is revolved. A coil-spring M is secured at its lower end to the rear face of the end stile D of the gate, a short distance above the pickets of the latter, and to the upper end of said spring is connected the rear end of a 60 wire cable h, which runs over a small pulley n, mounted on the stile a little above said spring. This cable thence passes to the grooved pulley G and runs one and two-thirds time around it, and is then carried over a 65 second small pulley O, mounted in a bracket P, extending rearwardly from post B. After passing through said bracket over said pulley the cable runs forward, parallel with the bracket, and extends to the forward stile D 70 of the gate, over a pulley L, mounted thereon, and thence downward contiguous with the front face of said stile, and is connected to the outer end of the latch R. This latch is pivoted at its rear end to one of the pickets 75 of the gate and has limited play in a slot r in the stile D. It is given a constant downward tendency by the coil-spring S, which connects it between its pivotal point and the stile with the bottom rail U of the gate. This forward 80 stile B is cut in two above the gate in line with the shaft H, forming an opening v, and the two sections thus made are joined by a horizontal U-shaped iron bracket W, extending forward, the purpose of which will be described 85 hereinafter. The forward post B is provided with a suitable latch receiving and retaining slot X.

The preferred construction of my device having been set forth, I will now proceed to 90 describe its operation. Supposing the gate to be in closed position, as shown in Fig. 1, the operator, from his seat in the wagon or other vehicle or other position, will grasp the crank I and turn it to rotate the shaft in the 95 direction indicated by the arrow. The revolution of the grooved pulley G thus produced will cause the cable h to be wound upon it and hence drawn back, lifting the latch R and releasing it from the slot X through the 100 medium of the connections which have been previously described. When the latch has reached its upward limit in the slot r upon continuance of the revolution of the grooved

pulley and consequent draft on the cable, it is apparent that the gate will be run back on the track E and the gap thus opened for the passage of the vehicle. When the gate thus 5 travels to the rear, the construction is such (the pulley O being located as described) that it will be carried back of the center post B. This is moreover allowed by the opening in the stile D, the arms of the bracket W passing 10 on either side of the shaft H, and thus permitting the entire gate to fall behind the post. The advantage of this arrangement is obvious. The full space between the post is left free for the passage of the vehicle, and 15 no portion of the gate projects to receive injury by being struck by passing objects. When the operator has passed through, he will manipulate the opposite crank in the opposite direction, and it will become readily apparent 20 by reference to Fig. 2 that the reverse operation will take place and the gate will be closed. I furthermore provide a pair of guiding or steady rollers T, bearing upon the upper surface of the top rail U of the 25 frame and mounted at the opposite ends of a bracket T' projecting rearwardly from the center post, whereby one roller will at all times have bearing on said rail.

The object of the coil-spring M at the rear 30 of the gate is to take up all slack in the cable h, and this cable has been found most satisfactory when composed of wire, as it will then remain always taut, and slipping of the same on the grooved pulley will be overcome.

35 The anti-friction hangers F and the track E are protected from snow and sleet by a covering or roof Z, which is secured on top of the beam C and overhangs said parts, thus forming a shed.

40 An advantage of my device which might be mentioned is that the gate need only be

of just the length of the gap to be closed, and thus economy in material results.

It is evident that in the construction and arrangement of parts of my device numerous 45 slight changes could be made by a skilled mechanic, and hence I do not confine myself to the peculiar construction shown, but consider myself entitled to all such variations as come within the spirit and scope of my invention. 50

Having thus described my invention, what I claim as new, and desire to secure by Letters Patent, is—

1. The combination of a gate, a supporting-frame, a shaft extending transversely through 55 said frame, a pulley rigid on said shaft, a cable secured at its opposite ends to the gate and encircling said pulley, and a loose pulley located out of vertical alignment with said rigid pulley, said cable being arranged to pass 50 over said loose pulley, whereby the gate is thrown back of the central supporting-post of the frame, as and for the purpose described.

2. The combination of a gate having upwardly-extending end stiles with a suitable 65 supporting-frame, a shaft extending transversely therethrough, a grooved pulley rigid on said shaft, a cable secured at its opposite ends to the gate and encircling said grooved pulley, and a loose pulley located behind said 70 grooved pulley, over which said cable passes, whereby the gate may be made to slide behind the central supporting-post, an opening being made in the forward gate-stile, and a suitable connection between the sections thus 75 formed, substantially as described.

In testimony whereof I affix my signature in presence of two witnesses.

GIDEON F. SHERWOOD.
